Attorney.

UNITED STATES PATENT OFFICE

GEORGE HUGHES, OF TROUT MILLS, ONTARIO, CANADA

FILL CAP

Application filed December 10, 1930. Serial No. 501,274.

The invention relates to improvements in fill caps as described in the present specification and shown in the accompanying drawings which form part of the same.

5 The invention has for its object the production of an efficient and reliable closure for the gasoline tank of an automobile, although it is equally susceptible of use for many other devices such as automobile radiators, and therefore it is not intended that its application shall in any way be restricted.

10 The invention comprehends a fill cap permanently attached to the filling tube in such a manner as to be readily swung to one side 15 thereof so as to uncover the opening. The cap by swinging to one side does not interfere with the pouring of fluid and moreover when closed seals the opening against leakage. A very distinctive feature lies in the 20 ease and rapidity by which the cap is opened and closed.

25 Referring to the accompanying drawings, Figure 1 is an elevation partly in section of a fill cap and filling tube to which the invention is applied.

Figure 2 is a similar view but showing the cap in an open position.

Figure 3 is a vertical cross section taken on the line 3-3 of Figure 2.

30 Figure 4 is a perspective view of a cam forming part of the mechanism of the invention.

Figure 5 is a plan view of a follower plate.

Figure 6 is a side view thereof.

35 Figure 7 is a perspective view of a spring that carries the follower plate.

Like numerals of reference indicate corresponding parts in each of the figures throughout the drawings of the invention.

40 In the embodiment of the invention selected for illustration, the reference numeral 8 designates the filling tube which may be of any suitable shape or design as also may be the fill cap 9 but which is shown as a disk-like member. The cap is of a larger diameter than the tube and is pressed thereon to close its opening 10 as later explained in detail. It is preferable to supply the cap with a gasket 11 of some customary material for precluding leakage, which gasket may be in

the form of a ring as shown attached in any desirable manner to the cap.

Integral with or secured to the underface of the cap is a pair of spaced lugs 12, 12, in which is pivoted by a pin 13 the follower plate 14 which has an extension 15 parallel with and in close proximity to the underface of the cap. This extension constitutes a finger, the use of which will later be explained.

45 The follower plate extends laterally and downwardly to the spring 16 to which it is pivoted by a pin 17 adjacent to the bent end 18 that is preferably equipped with a roller 19 for engagement with the cam 20.

50 The follower plate may be constructed of a flat pressed metal member having struck up sides that form flanges apertured to take the pins. A stop 21 may be struck up to abut the cam in order to limit the upward 55 movement of the follower plate in opening the cap.

55 The spring 16 consists of a flat piece of spring steel rigidly secured against the inner surface of the tube wall in any desirable 60 manner. The spring is bowed as clearly shown from an inspection of Figure 7 and has inwardly bent ends 22, 22, terminating short of each other. The extremities of the ends are bent to compose parallel lugs 23, 23, apertured to take the pin 17.

65 The cam 20 is curved at 24 to conform to the curvature of the filling tube to which it is secured by rivets 25 having countersunk heads. The spring 16 may also be secured by 70 these rivets by inserting it beneath the cam and notching it at 26 to permit the rivets to pass therethrough. The cam has two spaced flanges 27, 27, the edges 28 of which form the guiding surfaces. The uppermost portions of the flanges are inclined as at 29 leading downwardly to straight sections 30 that merge into outwardly curved portions 31, 31.

75 The roller 19 is resiliently held in engagement with guiding surfaces of the cam by 80 means of the tension of the spring 16.

85 From the foregoing it will be manifest that when the lid or cap is closed—Figure 1—the roller by its engagement with the inclined surfaces 29 of the cam forces the fol-

lower plate to press downwardly on the cap to tightly retain it on the filling tube. In opening the cap, as it is pulled upwardly the roller rides downwardly on the guiding surfaces 5 faces past dead centre of the spring pivot until it engages the curved guiding surfaces 31, 31, which reduce tension yet maintain the follower plate in a raised position with the stop 21 abutting the cam. In this open 10 position, Figure 2, the cap is situated to one side of the opening and cannot swing inwardly on the pivot pin 13 by reason of the finger 15.

What I claim is:—

15 1. In a device of the class described, a follower plate for pivotal attachment to the fill cap, supporting means for attachment to the interior of a filling tube, said supporting means being pivoted to said follower 20 plate in the vicinity of the plate's free end, and a cam for attachment to the interior of the filling tube to present a guiding surface engaged with the free end of the follower plate, said supporting means and said cam being relatively resilient so as to retain the 25 free end of the follower plate in engagement with the guiding surface.

2. In a device of the class described, a follower plate for pivotal attachment to the 30 under face of the fill cap and the interior of a filling tube so as to present a link connection therebetween, the pivotal connection of the follower plate to the filling tube being yieldable, a cam for attachment to the 35 interior of the filling tube, an angular element integral with said follower plate and engaged with said cam, and resilient means urging the angular element into engagement with the cam.

40 3. In a device of the class described, a follower plate for pivotal attachment to the underface of the fill cap so as to extend laterally and downwardly therefrom, a spring for attachment to the interior of a filling 45 tube, said spring being pivoted to the lower part of the follower plate adjacent to its free end, and a cam for interior attachment to the filling tube and engaged by the free end of the follower plate.

50 4. In a device of the class described, lugs projecting from the underside of the fill cap, a pin fitted therethrough, a follower plate pivoted to said lugs by said pin and extended laterally and downwardly from the fill cap, a 55 spring for attachment to the interior of a filling tube, said spring being pivoted to the lower part of the follower plate adjacent to its free end, and a cam for interior attachment to the filling tube and engaged by the 60 free end of the follower plate.

5. In a device of the class described, a follower plate for pivotal attachment to the underface of the fill cap so as to extend laterally and downwardly therefrom, a flat metal 65 spring lengthwise bowed and having incur-

vate ends terminating short of each other, the ends of said spring being pivoted to the lower part of the follower plate adjacent to its free end so as to exert a pull thereon, and a cam for interior attachment to the filling tube and engaged by the free end of the follower plate. 70

6. In a device of the class described, a follower plate for pivotal attachment to the underface of the fill cap so as to extend laterally and downwardly therefrom, a spring for attachment to the interior of a filling tube, said spring being pivoted to the lower part of the follower plate adjacent to its free end, and a stationary cam for interior attachment to the filling tube, said cam having a guiding surface engaged by the free end of the follower plate and shaped to vary the tension of the spring in the movement of said free end. 80

7. In a device of the class described, a follower plate for pivotal attachment to the underface of the fill cap so as to extend laterally and downwardly therefrom, means thereon for limiting the pivotal movement in one direction, a spring for attachment to the interior of a filling tube, said spring being pivoted to the lower part of the follower plate adjacent to its free end, and a cam for interior attachment to the filling tube and engaged by the free end of the follower plate. 90

8. In a device of the class described, a follower plate for pivotal attachment to the underface of the fill cap so as to extend laterally and downwardly therefrom, a limiting stop borne thereby, a spring for attachment to the interior of a filling tube, said spring being pivoted to the lower part of the follower plate adjacent to its free end, and a cam for interior attachment to the filling tube and engaged by the free end of the follower plate. 100

Signed at North Bay, Ontario, Canada, this fourth day of December, 1930.

GEO. HUGHES.
